UNITED STATES PATENT OFFICE

2,618,517

SPINDLE CONSTRUCTION

Gustaf Erikson, Benton Harbor, and Eddie Christian Filstrup, St. Joseph, Mich., assignors to Covel Mfg. Co., Benton Harbor, Mich., a corporation of Michigan

Application May 21, 1947, Serial No. 749,452

4 Claims. (Cl. 308—9)

1

This invention relates to improvements in spindle construction, particularly adapted, though not necessarily limited in its use, for grinding and precision boring machines, and one of the objects of the invention is to provide improved means whereby accurate machining of the work may be accomplished by controlling or regulating the film of oil between the bearings and spindle.

Another object is to provide improved means for preventing wobbling of the spindle, whereby close work and accurate machining may be performed.

A further object is to provide improved means whereby flexible hydraulic pressure may be exerted upon the bearings, to provide tighter fit between the bearings and spindle.

A still further object is to provide improved means whereby flexible hydraulic end thrust upon the spindle may be obtained.

To the attainment of these ends, and the accomplishment of other new and useful objects as will appear, the invention consists in the features of novelty in substantially the construction, combination and arrangement of the several parts, hereinafter more fully described and claimed and shown in the accompanying drawings exemplifying this invention, in which drawings

Fig. 1 is a longitudinal sectional view of a spindle of this character, constructed in accordance with the principles of this invention.

Fig. 2 is an enlarged detail sectional view of the motor end of the spindle.

Fig. 3 is an enlarged detail sectional view of the grinder or tool end of the spindle.

Fig. 4 is an enlarged detail transverse sectional view taken on line 4—4, Fig. 2.

Fig. 5 is a sectional view on line 5—5, Fig. 3.

Fig. 6 is a detail sectional view taken on line 6—6, Fig. 5.

Fig. 7 is a longitudinal sectional view of a modified form of the invention.

Fig. 8 is a top plan view of Fig. 7.

Fig. 9 is a sectional view on line 9—9, Fig. 8.

Fig. 10 is a detail sectional view taken on line 10—10, Fig. 7.

Referring more particularly to the drawings, the numeral 15 designates a spindle or shaft journaled in a bearing designated generally by the numeral 16 (Fig. 1), located adjacent one end, and in a bearing 17 adjacent the other end thereof. If the spindle is of sufficient length, intermediate bearings may also be provided. On one end of the spindle is a suitable tool, which, in the present exemplification of the invention, is shown

as a grinding element 18. This element is secured in position in any suitable manner, such as by means of clamping members 19—20, one of which is secured to the spindle, and the clamping members may be separably secured together by means of suitable fastening devices such as screws 21, or the like.

Mounted near the other end of the spindle is a motor 22, here shown as of the electric type, the motor being preferably disposed between the bearings 16—17.

An oil reservoir 23, of any suitable size and configuration, is suitably mounted, and forms a part of the bearing 16, or may be separate therefrom. A pump 24 has an inlet supply pipe 25 which communicates with the reservoir, and also a discharge pipe 26 that leads through a branch pipe 27 to an oil channel 28 that has communication with a space 29 between the spindle 15 and the inner surface of the bearing, whereby a film of oil or lubricant will be supplied to encompass or surround the spindle within the bearing. The discharge pipe 26 is also provided with another branch 30, which latter has communication with an oil passage 31 in the end bearing 17 of the spindle, for the purpose of creating pressure upon an end thrust bearing for the spindle, in a manner to be later described.

A pressure gauge 33 is provided in the pipe 25 to indicate the pressure exerted by the oil upon the bearings. In the branch pipe 27 there is provided an adjustable pressure regulating and relief valve 34, and a pressure gauge 35, and leading from the relief valve is a return pipe 34, which discharges back into the reservoir 23. In the pipe 30 is also provided an adjustable pressure regulating and relief valve 30^a, and a pressure gauge 30^b, and leading from the relief valve 30^a is a pipe 30^c that discharges back into the reservoir 23.

An extension 30^d leads from the pipe 30, and communicates with a passage 65, which latter communicates with cylinders 51, to operate the pistons 53, as will be later described. In the pipe 30^d is arranged an adjustable pressure regulating and relief valve 30^e, from which leads a pipe 30^f around the relief valve 30^e, and communicates with the pipe 30^c that leads back to the reservoir 23. A pressure gauge 30^f is also arranged in the pipe 30^d. With this arrangement, oil pressure at the bearings 16, 17, 35 and 36 and at the end 54 of spindle 15 (Figs. 2 and 4) may be determined by setting the relief valves 34, 30^a and 30^e.

It has been found that, in operation, the steadiness of the action of a spindle of this character,

under high speed, can be controlled by regulating or controlling the volume or thickness of the film of oil which surrounds the spindle within the bearings. That is, the thicker the film, the more the spindle will wobble under high speed of rotation. However, by reducing the thickness of this film, the more steady the spindle will rotate, and wobbling will be reduced to a minimum. This is very desirable, especially when the tool is used for accurate machining. To that end there is provided improved means whereby the thickness of the oil film about the spindle, as well as the lubrication of the spindle, may be readily controlled.

As shown in Figs. 4 and 5, the spindle bearing proper is formed of two members 35-36, which are slightly spaced from each other, as at 37, to provide a space to permit the oil to flow into and from the space directly surrounding the spindle, oil grooves 38 being also provided for that purpose.

The members 35-36 of the bearing are prevented from rotation, in any suitable manner, such as by means of keys 37^a. Arranged also within the housing portion of the bearing, are a plurality of cylinders 38^a, any number of which may be provided, and arranged in any suitable position and at any desired angle. In Figs. 4 and 5, two such cylinders are shown, which are arranged in inclined positions with respect to each other. In Fig. 4, each of these cylinders has communication through passages 39, with the oil passage 31, and, in Fig. 5 each cylinder 38^a communicates through passages 39 with the oil passage 28. If desired, the ends of the cylinders may be closed by plugs 40, or in any other suitable manner.

Within each of the cylinders is a piston member 41, the end of which may be shaped to form a reduced portion 42, to contact and bear against the bearing member 36. With this construction it will be seen that when the oil is forced from the tank or reservoir 23, by the pump 24, it will flow through the pipe 27 when the valve 34 is properly set, and into the oil passage or channel 28, from where it will flow, under pressure, into the cylinders 38^a, to act upon the pistons 41, which in turn will force the bearing member 36 toward the bearing member 35.

This will create a pressure upon the film of oil which encompasses the spindle between the bearing members 35-36, reducing the thickness of the oil film. This will be accomplished, as some of the oil film will be forced or squeezed out through the spaces 37 between the bearing members 35-36 and into the circulating oil system. Oil gets into the bearings by seepage through the pistons, and any excess oil will flow out through a drain pipe 43, suitably arranged.

At the forward end of the spindle there may be provided a suitable fluid seal, one form of which is shown in Fig. 2, wherein a diaphragm 44 is clamped between two members 45-46 by means of screws 47, and this diaphragm supports a seal member 48, that contacts and cooperates with another seal member 49.

At the other end of the spindle, means are provided for effecting an end thrust upon the spindle, shown more clearly in Figs. 1 and 2, wherein an end member 50 is provided with cylinders 51, any member of which may be employed, which cylinders may be arranged in any suitable manner with respect to the end of the spindle. These cylinders may be closed by plugs 52, and movable in each of the cylinders is a

piston 53. The adjacent end of the spindle 15 is preferably reduced, as at 54, and encompassing said reduced portion, so as to abut the shoulder 55 which is formed by said reduced portion, is a collar 56. This collar is keyed or otherwise fastened to the spindle, as at 57, and is provided with a peripheral flange 58, of a thickness preferably considerably less than the lengthwise dimension of the collar.

10 Encompassing the collar, and on each side of the flange 58, are collars or annular members 59-60. The collar 59 is secured to the bearing element 35 by means of a pin 62, so that the elements 35 and 59 will both be maintained against 15 rotation. The collar or annular member 60 is disposed on the opposite side of the flange 58, and in a position to be engaged by the reduced end 63 of the pistons 53. As the bearing element 36 is keyed to the bearing member 17 by 20 means of a key 37^a, these parts will be maintained against rotation.

25 Communicating with the oil passage 31, are passages 65, that lead to the cylinders 51, so that oil pressure may be exerted upon the pistons 53, to force them against the collar 60, which in turn will cause the collars 56 and 59 to be forced together to provide an end thrust upon the shoulder of the spindle. In addition to the lubrication obtained by seepage, a passage 66 is provided 30 for oil for lubrication, and passages 67 form communications with the inside of the spindle bearing. An additional passage 68 may be provided for supplying oil to the end of the spindle, and this latter passage has communication with 35 the passage 66.

35 Suitable sealing means may be provided for the spindle between the bearing 17 and the rotor, and may embody a diaphragm 69, clamped between the bearing 17 and a collar 70 by means of 40 screws 71, and this diaphragm supports a sealing element 72 that cooperates with a sealing element 73.

45 The rotor 74 of the motor may be secured to the spindle 15 in any suitable manner, such as by being clamped between two collars 75-76, the latter being threaded upon the spindle, as at 77, the collar being anchored, as at 78, and the rotor being splined on the spindle by a key, as at 79.

50 Figs. 7-10 illustrate a modified form of the invention in which the spindle 87 is mounted in a frame 88 having a removable head portion 89, the parts 88 and 89 being held together by fastening devices 83. The frame member 88 supports spaced bearings at the opposite ends of the spindle. Each of these bearings comprise lower and upper bearing elements 90 and 91, which are similar to the elements 35 and 36. The frame 88, however, provides generally rectangular cavities 81 for receiving the elements 90 and 91, the general contour of which is rectangular. These elements 90 and 91 are adapted to be forced together, for the same purpose as the elements 35 and 36, by means of piston elements 92 operating in cylinder cavities 93 formed in the head 89, oil under pressure being supplied in the cylinders 93 behind the pistons 92, through supply conduits 94, channels 95 and cylinder connecting ducts 96. The pistons 92 may thus be thrust under hydraulic pressure, to press elements 90 and 91 together upon the spindle, oil being forced or squeezed out through the openings or spaces 86 between the elements 90 and 91.

75 Within the bearing support member 88, there is

provided a chamber 97, in which is arranged a collar 98, supported by the spindle, and secured thereto by fastening devices such as screws 99. A collar 100 having an oil groove 101, also encompasses the spindle, and is disposed adjacent the collar 98. A support 102 encompasses the spindle and abuts a shoulder 103 in the member 88. Disposed between the support 102 and the collar 100, is a cylinder and piston carrying member 104, in which there is provided a plurality of cylinders and pistons 105-106, of a construction similar to the cylinder and piston elements 38-41, and the cylinders receive oil, under pressure, from a supply pipe 107, and suitable connecting passages. A fluid tight connection or adjustable joint 108 is provided for the supply pipe 107.

Thus when fluid pressure is admitted into the cylinders 105, the pistons 106 will force the collar 100 against the collar 98, to provide end thrust for the spindle.

At each end of the spindle 87, there is provided suitable sealing means. At one end of the spindle the seat embodies a collar 109, which abuts a sealing element 110, and is held in engagement therewith by means of a coiled spring 111 that is suitably supported by the spindle and is held in position longitudinally of the spindle by the bearing members 90 and 91 at one side of the spring and an annular member 113 at the other side of the spring. The annular member 113 is held in position through the medium of screws 114. One end of the spring engages a bearing surface 115 on the collar 109, and the other end contacts a shoulder 116 on the bearing 91. The member 113 is provided with a recess 117 in its outer face, and an annular member 118 has a recess 119 in its inner face, positioned that the recessed portions 117-119 interfit.

At the other end of the spindle is a somewhat similar seal embodying a coil spring 111^a, sealed in a recess 88^a, one end of the spring abutting a shoulder 116^a, and the other end contacting a bearing surface 115^a carried by a collar 109^a. This collar is provided with a sealing surface 109^b that abuts a sealing surface on a collar 87^a, sealed in an opening in an annular member 113^a held in place by screws 114^a. Another collar 113^a is threaded upon the spindle, as at 87^b, for holding these parts in assembled relation, and the collar 109^a is maintained against rotation preferably by anchoring pins 113^b.

If desired, the bearing may be water-cooled by providing a water circulation chamber or passage 121, having an inlet 122, and an outlet 123, the bottom of the chamber being closed by a suitable closure 124, such as a plate or the like.

It is thought that the operation of this improved spindle construction will be clearly understood from the foregoing, but, briefly stated, it is as follows:

The bearings are filled with the lubricant by the seepage of oil through the pistons. The oil seepage past the pistons 41 (Fig. 4) will enter the cavity around the bearings 35 and 36, and will travel to the left-hand end of the bearings, viewing Fig. 2, within the seal 72, and will travel through the grooves 38, to lubricate the spindle. A return pipe 73^a is provided, which leads back to the reservoir 23. A similar return pipe 73^b is provided at the other end of the spindle (see Fig. 1).

The portion of the spindle within the bearings will be coated with a film of oil, which, under

ordinary working conditions, is of a thickness somewhat greater than the thickness of the film when the device is used for accurate machining. When employed for general or rough work, it is not as important to control the wobbling action of the spindle as it is when doing finer or more accurate machining. Therefore, when performing the latter work, such motion of the spindle should be controlled, and the wobbling motion under high speed should be reduced to a minimum. This is accomplished with the present invention by increasing the pressure upon the oil, which acts upon the pistons. Under this pressure, the bearing elements which encompass the spindle will be forced together; that is, the movable member will be forced towards the other member, to reduce the thickness of the oil film. Under such pressure, the excess oil will be forced or squeezed out of the bearings through the spaces between the bearing elements and into the circulating system. Therefore, the action of the spindle can be controlled by controlling the thickness of the oil film.

Similarly, an end thrust is obtained through the medium of the end cylinder and piston elements. This is also accomplished without any detriment to the general lubricating system for the spindle.

One of the advantages of the present invention is that the bearings are adjustably flexible, so that when the spindle gets hot and expands, the bearings will also be permitted to expand slightly, so that, regardless of the temperature, the load will be uniform in regard to the setting of the relief valves.

While the preferred forms of the invention have been herein shown and described, it is to be understood that various changes may be made in the details of construction, and in the combination and arrangement of the several parts, within the scope of the claims, without departing from the spirit of this invention.

What is claimed as new is:

1. In combination, a frame providing spaced spindle bearings, a rotatable spindle journaled in said bearings, means forming a shoulder on the spindle, between said bearings and intermediate the ends of the spindle, a piston support member embracing said shaft adjacent said shoulder, said member being formed with piston cavities opening toward said shoulder, piston elements supported in said cavities, means to apply fluid pressure in said cavities behind said pistons to thrust the same toward said shoulder to impart end thrust on said spindle.

2. In combination, a frame providing spaced spindle bearings, a rotatable spindle journaled in said bearings, means forming a shoulder on the spindle, between said bearings and intermediate the ends of the spindle, a piston support member embracing said shaft adjacent said shoulder, said member being formed with piston cavities opening toward said shoulder, piston elements supported in said cavities, means to apply fluid pressure in said cavities behind said pistons to thrust the same toward said shoulder to impart end thrust on said spindle, said piston support member being formed as an element separate from the frame and mounted on a seat formed in the frame in position spaced from and facing said shoulder.

3. In combination, a frame providing a spindle bearing, a rotatable spindle journaled in said bearing, means forming a shoulder on the spin-

dle, a piston support member formed with piston cavities opening toward said shoulder, piston elements supported in said cavities, means to apply fluid pressure in said cavities, behind said pistons, to force same toward said shoulder to impart end thrust on the spindle.

4. In combination, a frame providing a spindle bearing, a rotatable spindle journaled in said bearing, means forming a shoulder on the spindle, a piston support member formed with piston cavities opening toward said shoulder, piston elements supported in said cavities, means to apply fluid pressure in said cavities, behind said pistons, to force same toward said shoulder to impart end thrust on the spindle, said piston support member being formed as an element separate from said frame and removably secured on an annular seat formed in said frame in position axially spaced from said shoulder.

GUSTAF ERIKSON.
